UNITED STATES PATENT OFFICE.

WILLIAM EDGAR ABBOTT, OF BEND, OREGON, ASSIGNOR, BY DIRECT AND MESNE ASSIGNMENTS, TO ABBOTT INCORPORATED, OF BEND, OREGON, A CORPORATION OF OREGON.

WASHBOARD.

1,427,048.

Specification of Letters Patent. Patented Aug. 22, 1922.

Application filed July 21, 1919, Serial No. 312,219. Renewed January 27, 1922. Serial No. 532,256.

To all whom it may concern:

Be it known that I, WILLIAM EDGAR ABBOTT, a citizen of the United States, and a resident of Bend, in the county of Deschutes and State of Oregon, have invented a new and Improved Washboard, of which the following is a full, clear, and exact description.

This invention relates to laundry appliances and has particular reference to washboards.

Among the objects of the invention is to so improve a washboard as to facilitate the grasping of a cake or bar of soap supported thereon. It is well known that a bar of soap supported upon a ledge or shelf of a washboard is particularly difficult to grasp and lift from its support because the soap is slippery due to the wet condition of the laundress's hand. This difficulty in the lifting of the bar of soap is increased in proportion to the thinness of the bar.

Among the objects of the invention, therefore, is to provide a support for the bar of soap which constitutes in effect a lifter or ejector therefor and so designed as to cause the delivery of the bar of soap directly into the laundress's hand, the manipulation of the device requiring no effort, skill, or loss of time on the part of the operator.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a perspective view of the upper end of a washboard showing my improvement.

Fig. 2 is a vertical sectional view of the same and indicating the manner of manipulation of the ejector.

Fig. 3 is a vertical sectional view of the adaptation of my improvement to a double faced or reversible washboard.

Fig. 4 is a transverse section on the line 4-4 of Fig. 3; and

Fig. 5 is a plan view of the ejector detached from the frame.

In the practice of this invention it is not my purpose to depart materially from any well known or established design or construction of washboards with respect to the rubbing surface 10, side bars 11 and head piece 12, holding that it is feasible for my improvement to be applied without material re-construction to any existing type of boards.

Ordinarily a ledge bar 13 extends transversely between the side bars 11 which serves two immediate purposes: First, to constitute a stiffener and support for the upper edge of the rubbing surface 10, and secondly as a support for the bar of soap in connection with another member such as a backboard 14 fitted between the side bars 11 and extending downward from the head piece to any desired distance with respect to the ledge bar. From what has been stated above it will be understood that in the practice of the washboard the bar of soap is supported temporarily against the backboard 14 and the upper surface of the ledge bar 13 when not held in the laundress's hand. This location for the soap is convenient for the reason that it is within easy reach of the operator. From the nature of the commodity, however, the bar of soap is disposed to adhere to the surface of the board 14 making it difficult to lift it therefrom, especially when the bar has become worn and thin from use.

To obviate this difficulty, I employ a movable member 15 constituting an ejector or lifter for the bar of soap whereby the operator may easily reach sufficiently far around the bar to remove it forcibly from the holder if it is inclined to stick. As shown this lifter or ejector comprises a substantially rectangular panel pivoted at 16 on a horizontal axis between the head piece 12 and the ledge bar 13, the axis of the pivots being far enough above the backboard, as shown in Fig. 2, to permit the free tilting of the ejector within predetermined limits within the space between the head piece and the ledge bar.

In other words in its action the ejector is in the nature of a lever of the first class upon the lower portion or end

of which the bar of soap is normally supported as shown in Fig. 1 and in dotted lines in Fig. 2. In this position the action of the ejector is identical with the back-board of an ordinary washboard.

The portion of the ejector below the axis may be heavier than the upper portion and for simplicity of construction this result is obtained by placing the axis slightly above the center of the member 15, so that the ejector board normally lies or tends under the weight of the soap to lie in a position to receive the bar of soap so as to be protected or guarded by the ledge bar from sliding down the washboard, it being remembered that when the bar of soap is placed upon the support in wet dripping condition it does not possess the tendency to adhere to the support that it does after it has drained and become partially dried. Said axis, however, is located but slightly if any above the center of the panel 15. To grasp the bar of soap in my improvement the operator simply presses downward with her thumb upon that portion of the ejector above the axis causing the lower portion of the ejector to swing upward thereby delivering the bar of soap directly into her hand. In other words during this pressure of the thumb against the upper portion of the ejector above the horizontal axis thereof the fingers of the same hand naturally drop beneath the lower edge of the ejector and around the bar of soap in position to receive the bar when the thumb is brought down grasping the upper edge of the bar of soap. With this positive grasp of the bar the soap may be either lifted directly from the support or moved downward therefrom.

The ejector panel 15 may be made of any suitable cheap but durable material such as wood and when so made pivots may be provided by stamping or pressing outward upon sheets of metal which as shown in the detail views may be formed to provide edge reinforcements 17 for the end portions of the panel. These strips of metal bent or otherwise formed into channels serve not only as reinforcements and stiffeners for the ends of the panels 15 and as carriers for the pivots 16, but also constitute drainage features or gutters down and along which the suds may flow instead of going over the ends of the tilting member. This feature is particularly applicable in the

adaptation of my improvement to the double faced washboard as illustrated in Fig. 3 wherein the ejector takes the place of the backboard 14.

As shown in Fig. 4 the tilting ejector member 15' is pivoted midway between the upper and lower edges of the bars 11 and is limited in its tilting movements by stops 18 in the nature of strips fastened to the lower or inner surface of the head piece 12'. The action of the ejector 15' in its co-operation with the ledge bar 13' is exactly the same as has already been described. Obviously the board as shown in Fig. 3 is reversible so as to bring the other rubbing face 10 or 10' into service, and whichever face of the board is upward the lower heavier end of the panel 15' will always project downward so as to receive the bar of soap above it just as is shown in Fig. 1. The delivery or ejection of the soap from the support is effected in this form of the invention in the same manner as has been described. The channel members 17 in this form of the invention are relied upon to direct the suds downward so that there will be no drip on the outside of the tub, it being noted that each of these channel members is provided with a flange 17' adjacent to the bar 11 over which the water or suds cannot flow. It will be noticed that the edges of the reinforcement 17 are bent to form channels receiving the ends of the panel and the edge of this reinforcement 17 is returned to form a gutter, as best shown at 17' in Figure 4, to form the drainage gutter hereinbefore referred to.

I claim:

1. A wash board having a tilting panel, means co-operating with the tilting panel to form a soap box, and means to pivot the panel for swinging movement around a horizontal axis, said pivot means comprising sheet metal reinforcing strips for the ends of the panel serving to hold the same from warping or deterioration, said strips being formed with integral pivot members projecting laterally therefrom.

2. A washboard having a tilting panel co-operating in forming a soap box and reinforcing strips embracing the ends of the panel and having return portions forming drainage gutters and pivoting means for the panel, as and for the purposes set forth.

WM. EDGAR ABBOTT.
